STEEL FRAME REFRIGERATOR CAR

Damian L. Reynolds, Hillsborough, Calif., assignor
of one-fourth to Luther L. Yates, one-fourth
to Loyd E. Cartmill, and one-fourth to James
King, all of San Francisco, Calif.

Application April 25, 1930, Serial No. 447,244

19 Claims. (Cl. 105—407)

This invention relates to a refrigerator car, and especially to one that utilizes a metal framework.

Steel refrigerator cars have the obvious advantage of strength, but they must be carefully insulated against transfer of heat to the car interior. It is well-known that metal parts, such as numerous rivets or bolts or braces that have surfaces exposed both inside and outside the car serve effectively to conduct heat into the car. Furthermore, they act as heat reservoirs, which are highly undesirable.

It is one of the objects of my invention to provide a refrigerator car, the frame of which includes steel bracing, which is totally encased by heat insulating material. Thus the loss of refrigeration by heat transfer is very materially reduced.

It is another object of my invention to provide a girder type of structural steel construction for such cars in which the metal is utilized most advantageously, and preferably by utilizing braces that are in tension rather than in compression. These girders, in my preferred form, are supplemented by plates and sills of insulation material, such as wood, which serve to take substantially all of the compressive stresses.

In refrigerator cars it is often desirable to remove the car structure from the underframe or chassis, to repair or replace parts. In steel cars as heretofore made, no great care has been taken to facilitate such removal. It is another object of my invention to provide a car structure in which the superstructure can easily be removed without disturbing the parts, and as a unit. This is accomplished by the use of a bolted construction holding the car body and the chassis together. The bolts can be tightened as required to overcome any tendency toward looseness due to warping, shrinking or sidesway.

It is another object of my invention in general to simplify the structure of such refrigerator cars, as by the reduction of parts making up the car frame.

It is still another object of my invention to provide a combination steel and wood car in which no mortise and tenon joints are used, whereby replacement of broken parts is simplified.

In refrigerator cars, it is customary to use floor racks in the cargo space upon which the cargo is placed. This ensures against moisture, which may find its way into the cargo compartment, damaging the goods. It is still another object of my invention to provide a simple and improved

form of holding means for these racks, and especially by the aid of metal clips attached to the steel framework.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

Referring to the drawings:

Fig. 1 is a side elevation of a refrigerator car embodying my invention, the left hand portion being shown in section;

Fig. 2 is an enlarged detail section of the lower side portion of the car;

Fig. 3 is an enlarged detail section of the roof structure;

Fig. 4 is an end view of the car;

Fig. 5 is a transverse sectional view, taken partly through the ice compartment and partly through the cargo compartment;

Fig. 6 is an enlarged section of the longitudinal sill structure taken through the cargo compartment;

Fig. 7 is a horizontal longitudinal view, the lower half being a section above the sills, and the upper half being a plan of the substructure, with the wall structure in section;

Fig. 8 is a fragmentary side elevation showing the side door and jamb structure;

Fig. 9 is a vertical section, taken along plane 9—9 of Fig. 8;

Fig. 10 is a horizontal sectional view, taken along plane 10—10 of Fig. 8;

Fig. 11 is a detail section taken along plane 11—11 of Fig. 8;

Fig. 12 is a fragmentary transverse vertical section, taken through the door, and shortened in order to reduce the size of the figure;

Fig. 13 is a fragmentary transverse section, taken near the top or roof of the car;

Fig. 14 is a fragmentary horizontal section, taken near the corner to show the corner post construction;

Fig. 15 is an elevation of the truss or girder construction at the car end;

Fig. 16 is an elevation of the truss or girder construction at the sides of the car;

Fig. 17 is a diagrammatic perspective view of the complete framework incorporating my invention;

Fig. 18 is an enlarged side section of a portion 5 of the framework showing how the floor racks are supported; and

Fig. 19 is a plan view of the parts shown in Fig. 18.

In general, the refrigerator car has the usual 10 chassis or running gear, including the longitudinal beams 21 (Figs. 1 and 5), and wheels 22 (Fig. 1). Transverse beams such as 23 (Figs. 1, 5 and 6) are also indicated. Forming a rectangular frame directly above the beams 23, are a series of angle 15 irons 24, 25 (Figs. 1, 2, 5, and 6). These angle irons have their horizontal legs permanently attached to the beam structure 21. The vertical legs form a frame to accommodate the wood sill beams 26, 27 (Figs. 2, 5, 6, 9, 12, 17). Longitudinal 20 wooden beams 28 (Figs 5 and 7) are fastened permanently to the cross beams 23.

Fastened directly to the sills 26 are the transverse tongue and groove floor boards 29 (Figs. 2, 5, 6, 7, 18). As shown most clearly in Fig. 25 2, these floor boards are omitted beneath the ice compartment 30, and a metal pan 31 forms the bottom of this compartment. The structure forming the ice compartment 30 at each end of the 30 car will be described hereinafter. It is sufficient at the present time to note that the metal pan 31 extends substantially entirely across the car at each end thereof and forms a bottom portion depressed below the top surface of the floor boards 29.

35 The entire car superstructure is supported on the sills 26, 27. This is useful because this superstructure can be removed from the frames formed by the angle irons 24-25 when desired, for replacement or repair. In order to facilitate the removal of this superstructure, use is made of a series of fastening devices that pass through the sills 26, 27 and that can be unfastened exteriorly of the car. Thus, as shown most clearly in Figs. 40 5, 6, and 7, a series of bolts 32 serve to hold the structural steel framework to the top of these 45 sills. The bottom angle irons for the structural steel framework are indicated in Figs. 5, 6, 7, 15, 16 and 17 at 33, 34 and will be described in detail later. These bolts 32 have an intermediate 50 enlarged portion 34' (Fig. 6) accommodated in a recess 35 at the bottom of the sill 26 and 27, whereby by tightening the nuts 36, the structural steel framework or truss can be rigidly and permanently attached to the top surfaces of the sills 55 26-27. Each of the bolts 32 also has an extension 37, which extends through appropriate apertures in the horizontal flanges of angle irons 24, 25. These extensions are threaded to accommodate the fastening nuts 38. It is apparent that 60 by removing these nuts 38 from each of the bolts 32 in the series, the entire superstructure can be lifted off the chassis.

65 Before proceeding further with a description of the side end and wall structures of the superstructure, I shall explain how the heat insulation layers are applied to the floor. Referring particularly to Figs. 5, 6, and 12, there is shown a wood layer 39 supported on the horizontal flanges 70 of the angle irons 40 fastened to the sills 26. Directly above this layer of wood, there is disposed hair or felt insulation 41 held in place as by the cleats 42. Above the cleats 42 is disposed a layer 43 of rigid insulation material, such as celotex. 75 Spaced above this rigid layer is another layer of

compressible hair or felt 44 held in place by the cleats 45.

One of the important features of my invention resides in the use of structural steel or metal frames or trusses to form a framework for the longitudinal sides of the car as well as the ends of the car. I shall first describe the truss framework for the sides of the car. Referring more particularly to Figs. 5, 6, 7, 13, 14, 16 and 17, there are shown the longitudinal lower horizontal angle 10 irons 33. These angles are placed immediately on top of wooden sill 26, as explained heretofore. There is an interruption at the center portion of the car to provide a door opening on each side of the car as indicated more particularly in Figs. 16 15, and 17. Vertical members, such as 45, formed of angle irons are used in conjunction with the longitudinal top brace 46 to provide in general a rectangular structure. This brace 46 extends throughout substantially the whole length of the 20 car and across the door openings. Slanting braces 47, tied to the other angle irons 33, 45 and 46 are also provided to ensure sufficient rigidity. For fastening the braces 47, use is made of gusset plates, such as 48. Horizontal bracing 49 is also 25 indicated. These are in the form of wooden joists and are held in place as by angle clips 50. The top angles 46 carry the longitudinal horizontal corner beams 51, as by the through bolts 52 extending through the horizontal flange of the angles 46. 30 Forming the ceiling of the car, there is a wooden tongue and groove structure 53 (Figs. 3, 5, 12 and 13) which extends across the car except where the hatch openings 54' are located for loading the ice compartment. This tongue and groove wood 35 ceiling is supported in a manner to be hereinafter described. To provide additional heat insulation at the ceiling, a layer of celotex 54 spaced above the ceiling structure 53 is provided; and over this are disposed several layers of hair, felt, or the 40 like 55.

These various layers 53, 54 and 55 are suspended from the roof of the car in any appropriate manner. For example, the ridge beam 57 and the spaced beams 58 upon which the roof 45 boards 59 are fastened can serve as a support for transverse suspension members 60 (Figs. 1 and 3). These members 60 have horizontal portions extending over the layers 55. Underneath the celotex layer 54 are disposed the transverse fastening strips 61. To the lower surfaces of these transverse strips are nailed or otherwise attached the tongue and groove ceiling boards 53.

I shall now describe the manner in which the end trusses are made and supported at the two 55 ends of the car. The end trusses are shown in a somewhat diagrammatic fashion in Figs. 15 and 17. Since both end frames are similar in structure, but one of them will be detailed.

The cross sills 27 (Figs. 2, 15 and 17) are fastened to the end angle irons 25 in a manner similar to the fastening of the side sills 26 to the side angle irons 24. Spaced immediately on the top surface of this cross sill 27 is the framework, including a horizontal angle 62. Vertical side angles 63 are joined to the lower angle 62 as well as to the top angle 64. Intermediate vertical angles 65 are also provided, as well as the cross braces 66. Gusset plates 67 serve to tie these various braces and angles together. Horizontal wood 65 beams or plates 68 are fastened to the vertical members 63, 65, as by the angle tie plates 69.

70 As shown most clearly in Figs. 7, 14 and 17, the side and end trusses are attached to the vertical corner posts 70. Each of these corner posts has a 75

surface coating with the end angles 45 and 63. Bolts 71 are indicated in Fig. 14, and hold these vertical angle members 45 and 63 to the corner posts.

5 It is particularly to be noted that these corner posts 70 are squared at both the top and bottom, as indicated in the diagrams of Figs. 15, 16, and 17. Due to this feature, replacement or removal of these corner posts is much more easily accomplished than if mortise and tenon joints were utilized. The door posts 72 are similarly fastened to the contiguous upright angles 45. These posts are also square ended, for ready removal and replacement.

10 15 The lower surfaces of these posts of course rest upon the sill beams 26 and 27, to which they may, if desired, be attached. Their upper surfaces contact with the top longitudinal beams 51, as well as to the transverse beams 73 (Fig. 17).

20 25 This combination wood and steel framework, as just described, presents many advantages. Due to the incorporation of the wood corner posts and the wood horizontal braces, such as 49 and 68, it is a simple matter to attach multiple layers 30 35 of heat insulating material both to the inside and the outside of the structure. In this way the steel framework is completely enclosed, none of the two surfaces being exposed either inside or outside of the car. Thus there can be no substantial heat transfer through the metallic members of the truss structures. It is further to be noted that the wood and steel members of the truss structures are so chosen that the wood takes the greater part of the compressive stresses, and 35 40 the steel takes the greater part of the tensile stresses. Due to this arrangement, lighter steel work can be utilized, while yet maintaining the strength of the truss structure at its high desired value.

40 I shall now describe how the insulation layers are supported and placed over both the inside and the outside of the car.

45 Referring now to Figs. 5, 6, 9 and 14, there are slabs 74 of celotex or other comparatively rigid insulating material placed on the inside of the car and supported on the corner post 70, the door post 72 and on the wood members 49 and 68. Disposed over these slabs 74 are the compressible felt or hair layers 75. These extend from the floor to the ceiling as indicated most clearly in Figs. 6 and 12. They can be held in place at the bottom between the cleats 76 and 77 (Fig. 6) and at the top by the cleats 78 engaging an overhanging shoulder of the top beams 51. Vertical cleats 79 (Fig. 14) cooperate with the corner post 70 for attaching these layers 75 thereto; and intermediate cleat supports 80 and 81 (Fig. 7) are utilized to keep these insulation layers in place 60 along the side of the car.

65 To form the inner walls of the car the usual tongue and groove boards 82 can be provided which can be supported on the cleats 78, 79 and 80. It is thus apparent that all of the layers 74, 75 and 82 can be supported on the wood posts of the truss members. Although one particular means for holding these insulation layers is indicated, it is apparent that other means could readily be provided. The important point is that there are no metal rivets or bolts passing through the insulation layers and through the steel members of the truss frames. In fact, as shown most clearly in Fig. 5, the insulation layers can be held 70 additionally in place by horizontal cleats, such as

83, cooperating with the horizontal brace members, such as 49.

5 The external insulation is applied in a somewhat analogous manner. Slabs 84 of celotex or the like are fastened to the wooden members such as 49 and 51 to form an external layer. Over this is disposed one or more layers of hair or felt 10 15 20 25 30 35 40 45 50 55 60 65 70 75 80 85. These two layers 84 and 85 can be held in place by horizontal and vertical cleats, such as 86 (Fig. 12), 87 (Fig. 14), 88 (Figs. 5 and 6). Disposed over this layer 85 is a matched wood layer 89 which is made of tongue and groove material, as shown most clearly in Figs. 4 and 14. This external wood layer (Figs. 4 and 5) extends up and under the eaves of the roof boards 59 and is held in place by the aid of cleats 90. As is usual, a running board arrangement 91 supported by a number of straps 92 can be provided. Hatch covers 93 are also indicated in Fig. 5.

The door structure is indicated most clearly in Figs. 8, 9, 10, 11 and 12. In these figures, there are indicated the two hinged doors 94, 95 having beveled contacting faces, such as shown in Fig. 11. The usual hinge handle structures can be provided. It is also apparent, as shown in Fig. 9, that the top and bottom surfaces of these door members slope inwardly so as to provide a tight closure against the ceiling and the floor. The doors 94 and 95 are placed in the frame formed by the vertical posts 72 and the sill structures. Door 30 35 40 45 50 55 60 65 70 75 80 85 90 95 96 98 99 100 102 103 105 106 107 108 109 110 111 112 113 114 115 116 117 118 119 120 121 122 123 124 125 126 127 128 129 130 131 132 133 134 135 136 137 It is apparent from the foregoing description that the steel framework used in the car is completely covered with heat insulating material, so that no part of it is in contact with the outside or the inside of the car. To the steel framework is attached the door sills, as well as the top beams, which take the majority of the compressive stresses, and which also serve effectively to insulate the steel frame from the interior of the car. It is also apparent that the whole superstructure can be removed by removing the nuts 38 from the bolts 32. Bolts 32 and 52 can be tightened as required to compensate for wood shrinkage. In order to facilitate repair all corner posts and door posts are made with square ends.

I claim:

1. In a refrigerator car, means forming the walls thereof, including a rigid metal framework, and heat insulating material substantially entirely enclosing said framework, and so arranged that substantially no part of the framework is in direct contact with conducting material on the exterior or interior of the car.
2. In a refrigerator car, a rigid structural metal framework for forming a wall structure for the car, and heat insulation material supported on said framework and substantially entirely enclosing the same and so arranged that substantially no part of the framework is in direct contact with conducting material on the exterior or interior of the car.
3. A refrigerator car having structural truss members for forming rigid wall supports, characterized by the provision of one or more layers of heat insulating material both on the inner and outer surfaces of the walls and so arranged that no part of said truss is in direct contact with conducting material on the exterior or interior of the car.
4. A metal car truss framework for the car wall, having metal top and bottom horizontal members, wood members secured to and overlying said top and bottom members, and heat insulation material supported on said framework and substantially entirely enclosing the same, and so arranged that no part of the framework is in direct contact with conducting material on the exterior or interior of the car.
5. A truss framework for forming a car wall, including horizontal top and bottom members of metal, metallic cross members connecting said horizontal members, horizontal wood beams, attached to the top and bottom horizontal members, and intermediate horizontal wood beams, and insulation material substantially entirely enclosing the metal framework, and so arranged that no part of the framework is in direct contact with conducting material on the exterior or interior of the car.
6. In a refrigerator car, means forming the wall of the car, including a truss structure having horizontal top and bottom chord members of metal, horizontal wood beams attached to the said chord members, one or more intermediate substantially horizontal wood braces between the top and bottom members, and a multi-layer heat insulation material fastened to the wood beams and braces on both sides of the truss.
7. In a superstructure for a refrigerator car, sills at the lower edges of the car, wall structures supported on said sills and permanently attached thereto, and fastening devices, accessible from the exterior of the car, for removably fastening the sills to a chassis structure, whereby

the superstructure can be secured to or removed from the chassis as a unit.

8. The combination as set forth in claim 7, in which the sills are held to the wall structures by bolts, and in which the fastening devices for the sills are extensions of said bolts.

9. In a refrigerator car, means forming the walls thereof, including a rigid metal truss, means forming the floor of the car, a floor rack covering the floor, and means forming the hinge support for the rack, said means being fastened to the truss, and insulation material substantially entirely enclosing the truss.

10. In a refrigerator car, a metallic framework providing a strong support for the superstructure, a chassis structure, said framework being characterized in that it is capable of being installed on or removed from the chassis structure as a unit, and an insulation material substantially entirely enclosing the framework, and so arranged that no part of the framework is in direct contact with conducting material on the exterior or interior of the car.

11. In a superstructure for a refrigerator car, sills at the lower edges of the car, said sills being formed of a material resistant to the conduction and transmission of heat, and metallic wall structures supported on said sills and permanently attached thereto.

12. In a superstructure for a refrigerator car, sills at the lower edges of the car, said sills being formed of a material resistant to the conduction and transmission of heat, wall structures supported on said sills and permanently attached thereto, and fastening devices, said fastening devices being accessible from the exterior of the car for fastening the sills to a chassis structure.

13. The combination as set forth in claim 12, in which the sills are held to the wall structures by bolts, and in which the fastening means are extensions of said bolts.

14. In a superstructure for a refrigerator car, sills at the lower edges of the car, said sills being formed of a material resistant to the conduction and transmission of heat, a metallic framework to provide strength for the superstructure of the car, said framework being supported on and permanently secured thereto, and forming with the sills a unit, capable of being installed on or removed from a chassis structure as such, and fastening means accessible from the exterior of the car for fastening the sills to the chassis structure.

15. In a superstructure for a refrigerator car, sills at the lower edges of the car, said sills being formed of a material resistant to the conduction and transmission of heat, a metallic framework to provide strength for the superstructure of the car, said framework being supported on and permanently secured thereto, and forming with the sills a unit, capable of being installed on or removed from a chassis structure as such, fastening means accessible from the exterior of the car for fastening the sills to the chassis structure, and a material resistant to the conductivity of heat for substantially entirely enclosing the framework.

16. In a metallic side and end framework constructed as a unit and adapted to be removably secured to the chassis of a refrigerator car, means secured to said metallic framework whereby an insulation material may be attached thereto in order to restrict the transfer of heat from the outside atmosphere to the interior of the car, and so arranged that no part of the framework is in

direct contact with conducting material on the exterior or interior of the car.

17. In a metallic side and end framework for a refrigerator car, means secured to said framework whereby an insulation material may be attached thereto in order to restrict the transfer of heat from the outside atmosphere to the interior of the car, and wood beams attached to the top and bottom of the sides of the framework, said wood beams forming with the framework a unit capable of being installed on or removed from a chassis structure as such.

18. In a metallic side and end framework for a refrigerator car, means secured to said framework whereby an insulation material may be attached thereto in order to restrict the transfer of heat from the outside atmosphere to the interior of the car, wood beams attached to the top and bottom of the sides of the framework, said wood beams forming with the framework a unit capable of being installed on or removed from a chassis structure as such, and fastening means

accessible from the exterior of the car for fastening the bottom wood beams to the chassis structure.

19. In a metallic side and end framework for a refrigerator car, means secured to said framework whereby an insulation material may be attached thereto in order to restrict the transfer of heat from the outside atmosphere to the interior of the car, wood beams attached to the top and bottom of the sides of the framework, said wood beams forming with the framework a unit capable of being installed on or removed from a chassis structure as such, and fastening means accessible from the exterior of the car for fastening the bottom wood beams to the chassis structure, said fastening means comprising elongated bolts and cooperating nuts for permanently attaching the framework to the bottom wood beams, whereby a means is provided from the exterior of the car for compensating for the expansion and contraction of the bottom wood beams.

DAMIAN L. REYNOLDS.
